SPRAYER

Tetsuya Tada, 2-6, 3-chome, Nishi-Nakanobu,
Shinagawa-ku, Tokyo, Japan

Filed Apr. 22, 1971, Ser. No. 136,629

Claims priority, application Japan Feb. 13, 1971

Term of patent 14 years

Int. Cl. D23—01

U.S. Cl. D23—17

FIG. 1

FIG. 2

FIG. 3

FIG. 5

FIG. 4

FIG. 1 is a front view of a sprayer showing my new design, the rear being a mirror image of the front shown; FIG. 2 is a plan view thereof; FIG. 3 is a bottom view thereof; FIG. 4 is a right side elevation thereof; and FIG. 5 is a left side elevation thereof.

I claim:

The ornamental design for a sprayer, substantially as shown and described.
